His Attorney

UNITED STATES PATENT OFFICE

ARTHUR P. JACKEL, OF PADUCAH, KENTUCKY, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed January 21, 1930. Serial No. 422,317.

My invention relates to railway traffic controlling apparatus, and particularly to apparatus of the type involving a railway switch and a signal governing traffic over such switch, both of which are governed from a remote point, together with an approach locking means operating when a train is approaching the signal to prevent the switch from being reversed until the expiration of a given time interval after the signal has been moved to the stop position.

One feature of my present invention is the provision of means operating under the conditions referred to above for requiring that the operator shall reverse the switch controlling apparatus in order to release the approach locking.

I will describe one form of apparatus embodying my invention, and will then point out the novel features thereof in claims.

The accompanying drawing is a diagrammatic view showing one form of apparatus embodying my invention.

Referring to the drawings, the reference character F designates a stretch of railway track which is divided by insulated joints to form a section B—C. Located in this section is a railway switch D leading into a siding F¹. Extending from one end of this section B—C is an approach section A—B, and extending from the other end of the section B—C is a second approach section C—E. Each of the track sections is provided with a track circuit comprising a battery 2 and a track relay designated by the reference character T with a distinguishing exponent.

Traffic over the switch D is governed by four signals S¹, S², S³ and S⁴, which signals are controlled by signal relays H¹, H², H³ and H⁴, respectively. As shown in the drawing, signal S¹ is provided with a circuit which passes from terminal X of a suitable source of current, through front contact 3 of relay H¹, and the operating mechanism of the signal S¹ to terminal O of the same source of current. The controlling circuits for the other three signals may be similar to the circuit for signal S¹, but they are omitted from the drawing to simplify the disclosure. The signal relays H are all controlled from a remote

point, such as an interlocking tower, and also by the track relay T^c as usual, but the controlling circuits for these relays are omitted from the drawing, because they form no part of my present disclosure.

The switch D is provided with an operating mechanism M, which in turn is controlled by suitable switch governing apparatus, this apparatus in the form here shown comprising two relays W^N and W^R. As explained in detail hereinafter, the control of the switch is such that the switch will be moved to its normal or its reverse position according as relay W^N or W^R is energized. The relays W are controlled from the same remote point as the H relays.

The reference character P designates a signal repeating relay, which relay is energized when and only when all four of the signal relays H are deenergized, that is, when and only when all four of the signals S indicate "stop". The circuit for relay P is from terminal X, through back contact 4 of relay H³, back contact 5 of relay H⁴, back contact 6 of relay H¹, back contact 7 of relay H², and the winding of relay P to terminal O.

The reference character L designates an approach locking relay, the circuit for which will be explained hereinafter. This approach locking relay is at times controlled by a slow pick-up relay N, and the latter relay is in turn controlled by a switch indication relay K as well as by the repeater relay P and the approach locking relay L.

The indication relay K is controlled by the switch D and by the switch relays W in such manner that the relay K is energized when and only when the switch and the relays register, that is, when and only when the switch is in the position corresponding to the condition of the relays W. As here shown, this control of relay K is accomplished through the medium of contacts on the relays W and a circuit controller G which is operated by the switch D. Assuming that the switch D is in the normal position, and that the normal relay W^N is energized and the reverse relay W^R deenergized, the circuit for relay K is from terminal X, through the back point of contact 14 of relay W^R, front point 100

of contact 15 of relay W^N , contact 16 of circuit controller G, winding of relay K, and contact 17 of circuit controller G to terminal O. If now the operator reverses the relays 5 W, so that relay W^N becomes deenergized and relay W^R becomes energized, the circuit just traced for relay K will become opened at contacts 14 and 15, so that this relay will become deenergized. After the switch D responds 10 by moving to its reverse position, relay K will again become energized, the circuit being from terminal X, through the back point of contact 15 of relay W^N , front point of contact 14 of relay W^R , contact 17 of circuit controller G, winding of relay K, and contact 16 of circuit controller G to terminal O.

The approach locking relay L is normally energized by a stick circuit which passes from terminal X, through back contacts 18, 19, 20 20 and 21 of the H relays, front point of contact 22 of relay L, and the winding of this relay to terminal O. This circuit is provided with a shunt around back contact 18 of relay H^3 , which shunt includes front contact 23 of track relay T^E . The circuit is further provided with a shunt around back contacts 20 and 21 of relays H^1 and H^2 , respectively, which shunt includes front contact 24 of relay T^A . The pick-up circuits for relay L will 25 be traced during the explanation of the operation of the apparatus.

Assuming that switch D is in the normal position, and that the operator desires to permit a train moving toward the right to pass 30 through the switch, he will cause relay H^1 to become energized, thereby causing signal S^1 to give a proceed indication. This will open one branch of the stick circuit for relay L at contact 20, but the relay will remain energized, because contact 24 of track relay T^A 35 is closed. When the train enters the approach section A-B, however, contact 24 of track relay T^A will open, so that relay L will become deenergized. When the train enters section B-C, relay H^1 will become deenergized, due to the opening of track relay T^E . A pick-up circuit for relay L will then become closed, which circuit passes from terminal X, through back contacts 40 18, 19, 20 and 21 of the H relays, back contact 28 of track relay T^E , and the winding of relay L to terminal O. The parts of the apparatus will then be restored to the conditions in which they are shown in the drawing, except that track relay T^E will be deenergized. 45

I will now assume that the operator desires to reverse the switch D. In order to do this, he will cause relay W^N to become deenergized and relay W^R to become energized. A circuit for the operating mechanism M will then be closed, which circuit passes from terminal X, through front contact 8 of relay L, front contact 9 of relay P, back contact 10 50 of relay N, front contact 11 of track relay

T^E , contact 13 of relay W^R , and the operating mechanism M to terminal O. In order to restore switch mechanism M to its normal position, the operator will cause relay W^N to become energized and relay W^R to become deenergized, whereupon the normal circuit for switch mechanism M will become closed, which circuit is the same as the reverse circuit which I have just traced, except that it will include contact 12 of relay W^N instead of contact 13 of relay W^R . It will be noted that both of these circuits for the switch mechanism M include front contact 8 of the approach locking relay L.

I will now assume that switch D is in the normal position, that the operator has cleared signal S^1 , that a train has entered the approach section A-B, and that the operator then desires to move the switch D to the reverse position. In order to do this, he will first restore signal S^1 to the stop position, but the approach locking relay L will remain open because its stick circuit is open at its own front contact 22, and its pick-up circuit is open at back contact 28 of track relay T^E . The operator will then reverse the conditions of the switch relays W^N and W^R , thereby causing the indication relay K to become deenergized. An operating circuit for the slow pick-up relay N will then become closed, which circuit passes from terminal X, through back contacts 18, 19, 20 and 21 of the H relays, back point of contact 22 of relay L, front contact 25 of relay P, back contact 26 of relay K, and the operating winding of the slow pick-up relay N to terminal O. Switch D will not reverse, because the circuit for the operating mechanism M will be open at contact 8 of relay L. After the expiration of the time required for the slow pick-up relay N to close, an auxiliary pick-up circuit for relay L will become closed, which circuit passes from terminal X, through the back contacts 18, 19, 20 and 21 of the H relays, front contact 27 of relay N, and the winding of relay L to terminal O. Relay L will then become energized, whereupon the operating circuit for relay N will become opened at the back point of contact 22 of relay L, with the result that relay N will again become deenergized. When relay L becomes energized, and relay N becomes deenergized, the reverse operating circuit for switch mechanism M will become closed, so that the switch will be moved to its reverse position. The operator may then cause relay H^2 to become energized, thereby clearing signal S^2 , so that the train in section A-B will be allowed to proceed through the switch.

It will be seen from the foregoing, that under normal conditions the slow pick-up relay N does not operate, but that when operation of this relay is required in order to release the approach locking, it is necessary for the operator to reverse the switch con-

trolling relays W before the circuit for relay N can become closed. In other words, relay N does not function until it is necessary to release the approach locking, and then it will not function without the cooperation of the operator.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a railway switch, two switch controlling relays governed from a remote point for causing operation of said switch to normal or reverse position according as one or the other of the relays is energized, a circuit controller operated by said switch, an indication relay controlled by said switch controlling relays and said circuit controller and energized or deenergized according as the switch does or does not register with the condition of the switch controlling relays, a signal controlling traffic over said switch and also governed from said remote point, an approach section located in the rear of said signal, approach locking controlled in the usual manner by traffic in said approach section and in accordance with the indication given by said signal for preventing operation of said switch, and means for releasing said approach locking requiring deenergization of said indication relay.

2. In combination, a railway switch, controlling apparatus governed from a remote point for causing operations of said switch, an indication relay controlled by said apparatus and by said switch and energized or deenergized according as the switch does or does not register with the condition of the apparatus, a signal controlling traffic over said switch and also governed from said remote point, an approach section located in the rear of said signal, approach locking controlled in the usual manner by traffic in said approach section and in accordance with the indication given by said signal for preventing operation of said switch, and means for releasing said approach locking requiring deenergization of said indication relay.

In testimony whereof I affix my signature.

ARTHUR P. JACKEL.
